UNITED STATES PATENT OFFICE.

GEORGE L. CHRISTMAN, OF SWISSVALE, PENNSYLVANIA, ASSIGNOR TO WESTINGHOUSE ELECTRIC & MANUFACTURING COMPANY, A CORPORATION OF PENNSYLVANIA.

KNIFE-BLADE SWITCH.

1,427,359.

Specification of Letters Patent. Patented Aug. 29, 1922.

Application filed January 30, 1920. Serial No. 355,047.

To all whom it may concern:

Be it known that I, GEORGE L. CHRISTMAN, a citizen of the United States, and a resident of Swissvale, in the county of Allegheny and State of Pennsylvania, have invented a new and useful Improvement in Knife-Blade Switches, of which the following is a specification.

My invention relates to switches and particularly to positioning or stop members for knife-blade electrical switches.

One object of my invention is to provide a device of the above indicated character that shall be extremely simple in construction, effective in operation and economical to manufacture.

Another object of my invention is to provide a positioning or stop member that shall be adapted for ready mounting on a knife-blade switch of usual form without any alteration in the switch.

Heretofore, it has been usual to provide stop members or devices to limit the movement of the blade members of knife-blade switches, certain of which have comprised relatively-complicated and expensive structures while others have required some, even if slight, special machining of the switch parts.

In practicing my invention, I provide an extremely simple and inexpensive member that may be readily mounted on any of a usual standard form of knife-blade switches without even the slightest alteration in the switch.

In the accompanying drawings, Figure 1 is a side elevational view of a knife-blade switch and a stop member embodying my invention; Fig. 2 is a partial front elevational view thereof; Fig. 3 is a view, similar to a portion of Fig. 1 of a modified form of switch embodying my invention; Fig. 4 is a view, similar to Fig. 2, of the device shown in Fig. 3, and Figs. 5 and 6 are views, similar, respectively, to Figs. 3 and 4, of a further modification of the device.

A switch 1, of a usual and well-known type, comprises, in general, a knife-blade member 2 having a handle 3, a pivot-terminal jaw member 4 on which the blade member is mounted, a pivot member or pin 5 and a terminal jaw member 6 for co-operation with the blade member.

55 Studs 7, on the members 4 and 6, and nuts

8 secure the switch to any suitable support, such as a switchboard panel 9.

A positioning or stop member 10, preferably constructed of a single piece of relatively-thin sheet metal, has apertured side portions 11, closely embracing the jaw member 4 and the pivot pin 5, and a flat transverse mid-portion 12 to arrest the blade member 2 at a position of the latter indicated by broken lines in Fig. 1. Punched 65 portions 13, in the side portions 11, are bent inwardly and around outer straight edges 14 of the terminal member 4 in relatively-flat abutting engagement therewith and, by extending on either side of a central horizontal axis through the member 5, rigidly hold the positioning member 10 in the position shown.

When it is desired to mount the positioning member 10 on any standard switch, of 75 substantially the type shown, the pin 5, the washers 15 and the nuts 16, that normally are parts of the switch, are removed and the member 10 is placed over the end of the member 4, after which the member 5, the 80 washers 15 and the nuts 16 are replaced.

In the modification of my device illustrated in Figs. 3 and 4, a member 17, preferably of strap metal, embraces the pin 5 on one side of the terminal member 4 and is 85 provided with punched portions 13, similar to the portion 13 of the device of Figs. 1 and 2, that engage the forward edge 14 of the terminal member 4. A member 18 of substantially L-shape is riveted or otherwise 90 secured to a laterally-displaced forward portion 19 of the member 17 and has a portion 20 projecting into the path of the blade member 2.

As illustrated in Figs. 5 and 6, the modification of my device comprises a member 21 of relatively-thin sheet metal bent to substantially U-shape having side portions 22 embracing the terminal member 4 and the pin 5 and transverse under portions 23 and 100 24 for receiving the blade member 2 and to engage the under side of the member 4 for preventing the turning of the member 21, respectively.

Not even the slightest alteration in the 105 switch parts is required in any of the forms of my invention, and the device is simple and economical in construction, effective in operation and very easy to install.

While I have shown and described par- 110

ticular forms of my invention, changes may be effected therein without departing from the spirit and scope thereof, as set forth in the appended claims.

5. I claim as my invention:

1. In a knife-blade switch, the combination with a knife-blade member and a pivot terminal member therefor, of means for holding the blade member in a predetermined position comprising a member constituted to be added to, without any alteration in, the switch.
2. A switch comprising co-operating members initially formed for a certain amount of unrestricted relative movement and means for holding one of said members in a predetermined position within the limits of said movement, said means being constructed for co-operative positioning on the switch without any alteration in the initial form of the switch.
3. In a knife-blade switch, the combination with a knife-blade member and a pivot terminal member therefor, of a member secured to said terminal member and having a stirrup portion extending across the path of the blade member to position the latter.
4. In a knife-blade switch, the combination with a knife-blade member and a pivot terminal member therefor, of a positioning member embracing the terminal member and having a portion adapted to positively engage the blade member.
35. 5. In a knife-blade switch, the combina-

tion with a knife-blade member and a pivot terminal member therefor, of a positioning member for the blade member embracing, and having a holding portion hooked over the outer perimeter of, the terminal member.

6. In a knife-blade switch, the combination with a knife-blade member, a pivot terminal member therefor and a pivot pin, of a positioning device for the blade member comprising a member co-operating with the pin having a holding portion crimped over the perimeter of the terminal member.

7. In a knife-blade switch, the combination with a knife-blade member, a pivot terminal jaw member therefor and a pivot pin, of a positioning member for the blade member embracing the jaws of the terminal member and mounted on the pin.

8. In a knife-blade switch, the combination with a knife-blade member, a pivot terminal jaw member therefor and a pivot pin, of a positioning member for the blade member embracing the jaws of the terminal member and mounted on the pin, said positioning member having an indented portion to prevent movement of the same with respect to the terminal member and a portion co-operating with the blade member to position the latter.

In testimony whereof, I have hereunto subscribed my name this 27th day of January 1920.

GEORGE L. CHRISTMAN.
